US00D736765S

(12) **United States Design Patent**
Li

(10) **Patent No.:** US D736,765 S
(45) **Date of Patent:** ** Aug. 18, 2015

(54) **TABLET PC**

(71) Applicant: **Matsunichi Communication Holdings R&D (Shenzhen) Co., Ltd.**, Shenzhen, Guangdong Province (CN)

(72) Inventor: **Xiaohong Li**, Shenzhen (CN)

(73) Assignee: **Matsunichi Communication Holdings R&D (Shenzhen) Co., Ltd.**, Shenzhen, Guangdong Province (CN)

(**) Term: **14 Years**

(21) Appl. No.: **29/475,711**

(22) Filed: **Dec. 5, 2013**

(51) **LOC (10) Cl.** 14-02

(52) **U.S. Cl.** USPC ..... **D14/341**; D14/138 AA

(58) **Field of Classification Search**

USPC ..... D14/315-318, 341-344, 129, 130, 496, D14/137, 138 R, 138 AA, 138 C, 138 G, 147, D14/203.1, 203.3, 203.4, 203.7, 389; D6/308, 310; D21/324, 329, 332; 455/556.2, 566; 379/916; 345/901, 345/905, 173; 361/679.26, 679.3, 679.55, 361/679.56

CPC H04M 1/0202; H04M 1/0279; H04M 1/0281; H04M 1/0283; G06F 1/1613; G06F 15/00; A63H 33/3016; G01S 17/74; G01S 17/08
